UNITED STATES PATENT OFFICE.

ELLIOTT E. FURNEY, OF ST. LOUIS, MISSOURI.

APPARATUS FOR CHECKING THE WASTE OF WATER.

SPECIFICATION forming part of Letters Patent No. 331,490, dated December 1, 1885.

Application filed June 12, 1884. Serial No. 134,677. (No model.)

To all whom it may concern:

Be it known that I, ELLIOTT E. FURNEY, of the city of St. Louis, in the State of Missouri, have invented a certain new and useful Apparatus for Checking the Waste of Water, of which the following is a full, clear, and exact description, reference being had to the accompanying drawings, forming part of this specification.

10 This device causes the flow of water to cease after a given quantity has passed through the discharge-spout, whether the device for turning on the supply is returned to the position in which it was found after opening the 15 apparatus or not.

It consists of a case having two chambers separated by a diaphragm, through which passes a valve-stem carrying a valve at each end, of which the diaphragm forms the seats. Around 20 the valve-stem are a number of passages, (or a single passage,) through which the water passes from the chamber in communication with the supply-pipe to the other chamber, which is in communication with the discharge-pipe. The water-passage is closed when either 25 valve reaches its seat. There is a duct controlled by a valve, through which the water may be allowed to flow from one chamber into the other. One of the valves of the stem is 30 made in the form of a piston, and fits the cylindrical chamber, so as to nearly close communication between the parts of the chamber above and below the valve-piston.

Figure 1 is an elevation of the apparatus. 35 Fig. 2 is a section at 2 2, Fig. 8, showing the valves ascending, the duct-valve being open. Fig. 3 is a detail section at 2 2, Fig. 8, showing the lower valve closed against its seat, and Fig. 6 is a similar section, showing the upper 40 valve closed upon its seats. Fig. 4 is a section at 2 2, Fig. 8, showing the valves descending. Figs. 5 and 7 are sections at 2 2, Fig. 8, illustrating the action of the automatic valves when the course of the water is upward. Fig. 8 45 is a transverse section at 8 8, Fig. 5. Fig. 9 is a modification showing the duct connecting the chambers passing through the stem of the automatic valves. Fig. 10 is a transverse section at 10 10, Fig. 9.

A is a case constructed in any suitable manner and of any suitable material, as cast-iron.

B and C are the induction and the eduction (or discharge) nipples.

I will first describe the device as shown in Figs. 2 and 4, in which the water passes downward through the valve-seat diaphragm, B being the induction, and C the eduction, nipple or passage.

D is a diaphragm perforated centrally for the passage of the stem E of the two automatic valves F and G. The central orifice of the diaphragm has a number of grooves forming channels d, through which the water passes freely when neither of the valves is closed; but when either of the valves is closed upon its seat on the diaphragm the passages d are stopped.

H and I are the cylinders in which the valves F and G work, the upper valve, F, fitting as a piston in its cylinder, the fit being so tight 70 as to prevent the free passage of water between the piston-valve F and the cylinder. A limited quantity of water is allowed to pass through or around the piston-valve, for a purpose to be hereinafter explained. This may 75 be provided for by making the piston to fit somewhat loosely in the cylinder or by boring a small hole, f, through the piston, as shown in the drawings. The lower end of the cylinder H does not reach the diaphragm D; but 80 there is a passage between them all around communicating with an annular chamber, J, extending around the lower end of the cylinder. The induction-passage B communicates with this annular chamber, and thus with the 85 interior of the cylinder H below the piston-valve. The interior of the cylinder H has at its lower end a beveled valve-seat, h, acting, in conjunction with the valve F, to close communication between the interior of the cylinder H and the induction-passage B. At the 90 same time the passages d and f are closed by the same valve, so that there is no communication between the lower cylinder, I, and the induction-passage, and no communication between the parts of the cylinder H which are 95 above and below the piston-valve.

K is a water pipe or duct extending from

the upper part of the cylinder H to the upper part of the cylinder I.

L is a cock in the duct, by which it may be closed.

5 The valves F G may have leather, rubber, or other faces F' G', or may be fitted to their seats with ground joints.

The head H' of the cylinder H is made flat to fit the flat upper side of the valve F and to form a seat therefor, so that when the valve is in its upper position no liquid can escape through the passage or duct K, nor between the valve and the cylinder, or through the passage f, (in the valve.)

15 The normal position of the cock L is open, as seen in Fig. 2, the valves F and G being in their upper position, so as to prevent any water passing into chamber I either through passages d or K. When it is desired to draw 20 water, the cock L is closed. The valves descend by the pressure of water above them as fast as the water can pass through the passage f. (See Fig. 4.) The water flows through the passages d and eduction C until the valve 25 F reaches its seats h D, when the flow of water ceases, the passage K being closed by the cock L and the passages d and f closed by the contact of valve F with its seat D. Now, to draw water, it is needed first to open the cock L 30 and then to close this cock. On opening the cock the valves F and G fly to their upper position, and on closing the cock the water to a given quantity flows out, as aforesaid. It will be seen that the top of valve F has greater 35 area than its under side, so that as water passes above it both valves will be forced downward by water-pressure. If the cock L is left open after the discharge of the water contained in the cylinder H above the valve F, there is no 40 further discharge, as the passages K and f are closed by the valve F and its seat, and the passages d are closed by the valve G.

I will now describe the action of the device when the nipple C is coupled with the supply-pipe and the water discharges through the orifice B. In this case, when the cock L is closed, the pressure from beneath the valve G lifts the valves, and when the cock is open the pressure on top of the valve F depresses the valves. The lifting of the valves can only take place slowly, as they are only allowed to ascend by the escape of water from above the valve through the passage f, or around the valve, whereas the descent of the valves on opening 55 the cock is rapid, as the water has free passage to the upper part of cylinder H through the duct K.

It will be seen that the manipulation of the cock L is the same in both cases, whether the water escapes through B or through C, the water in either case flowing for a limited time when the cock L is closed, after having been opened.

The direction of the water-currents is indicated by arrows, and the direction of the movement of the valves is shown by an arrow upon the valve-stem.

In Figs. 2 and 4 the water enters at B and escapes at C. Fig. 2 represents the valves in the act of rising as the cock L is opened. Fig. 70 70 4 represents the valves descending when the cock L is closed.

In Figs. 5 and 7 the water enters the apparatus at C and escapes at B.

Fig. 5 represents the valves descending as 75 the cock L is opened, and Fig. 7 shows the valves ascending, the cock L being closed.

It is not essential to the invention that the duct leading from the upper part of the cylinder H to the cylinder I should be located in any particular place or position, it being only essential that there should be a way for the water to pass to and fro between the cylinder I and the part of the cylinder H above the valve F, and that the same should be controlled by a valve or cock.

As one of many possible modifications, I show the duct passing through the stem E of the valves F G. (See Figs. 9 and 10.) The stem E has an axial bore, e e', from top to bottom, the upper part, e, of the bore being of greater diameter than the lower part, e', and between the parts is a conical valve-seat, e², of the conical valve L. This valve has a tubular stem, L', turning in the part e of the bore. 90 From the inside of the tubular stem a passage, l, extends through the face of the valve, said passage being closed by the valve-seat when the valve is in the position shown in Fig. 9; but when the valve is turned about one-half 95 around, the passage l is brought in conjunction or line with a passage, e³, in the valve-seat, and communication is opened between the cylinder I and the part of the cylinder H above the valve F.

As a means of operating the valve L, I show a stem, M, passing through a stuffing-box, N, and having at the lower end a cross-bar, m, whose ends occupy vertical grooves l', so that the tubular stem L' is made to turn with the stem M, while at the same time the valves F and G, with their connecting stem E, are left free to move up and down, while at the same time the stem M has no vertical movement. The stem E is prevented from 110 turning with the valve L by a feather, e⁴, that works in a seat made in the diaphragm D.

The operation of this device is similar to that described in relation to Figs. 2 and 4, as the valve L of this device is the exact equivalent in its office to the cock L of those figures, and the axial passage through the valve-stem E serves the exact purpose of the duct or passage K.

I claim—

1. Two chambers or cylinders in connection, respectively, with the water supply and discharge, and separated by a diaphragm through which passes a connecting stem of two valves, one of which has a small passage 120 and works as a piston in one chamber or cylinder, the other valve working free in the other chamber or cylinder, a passage for water through the diaphragm from one chamber 130

to the other, closable by either of the valves, and a duct controlled by a cock or valve leading from one chamber to the other.

2. Two chambers or cylinders in connection, respectively, with the water supply and discharge, separated by a diaphragm having a port connecting the chambers closed by valves working in the chambers, and connected by a stem passing through the diaphragm, and a duct leading from one chamber to the other, controlled by a cock or valve, the upper valve having a small passage.

3. The combination of a cylinder containing a valve working as a piston therein, and having a water-orifice in the side thereof, a valve-stem connecting said valve with another valve working in a chamber separated from said cylinder by a diaphragm or partition through which the valve-stem passes, and having a port closable by the valves, for the passage of liquid between the cylinder and chamber, a water-orifice in the chamber, the piston-valve having a passage to allow the water in given quantity to pass from one side of the piston-valve to the other side thereof, for the purpose set forth, and a duct controlled by a cock or valve leading from one end of the cylinder to the chamber.

4. The combination of cylinder H, with valve-seats h H', diaphragm D, with valve port or ports d , and orifice for the passage of valve-stem E, stem E, carrying valves F and G, constructed to close the passages between cylinder H and a chamber or pipe, I, a small passage through the upper valve, and a duct leading from the upper part of cylinder H to the chamber I, controlled by a cock or valve, L, for the purpose set forth.

5. The combination of a casing divided by

a diaphragm forming two chambers or cylinders, a stem provided with two valves to seat against the diaphragm, a small passage through the upper valve, a passage connecting the said chambers or cylinders between the valves, a duct connecting the said chambers or cylinders independent of the passage between the valves, and a cock or valve controlling the operation of the apparatus, the duct connecting through the valve-seat of the upper chamber, and with the lower chamber beneath the diaphragm.

6. The combination of a casing divided by a diaphragm forming upper and lower chambers, a stem passed through the diaphragm, having a valve at its upper end provided with a perforation, f , and seating against the diaphragm, and a valve at the lower end of the stem, also seating against the diaphragm, a passage through the diaphragm closed by either valve, a duct connecting the upper end of the upper chamber with the lower chamber, and a cock or valve in the duct for controlling the operation of the apparatus.

7. The combination of the casing, a diaphragm, D, having an orifice for the valve-stem, a valve-port, and dividing the casing into an upper chamber, H, having valve-seats H' and h , and a lower chamber, I, a stem, E, carrying valves F and G, seating on opposite sides of the diaphragm, a small passage through the valve F, and a duct leading from the upper part of the upper chamber to the lower chamber, having a cock or valve controlling the operation of the apparatus.

ELLIOTT E. FURNEY.
